MANUFACTURE OF SHOES

Chester D. Turner, Haverhill, Mass., assignor to
 United Shoe Machinery Corporation, Paterson,
 N. J., a corporation of New Jersey

Application December 17, 1935, Serial No. 54,867

7 Claims. (Cl. 12—142)

This invention relates to the art of shoemaking and is illustrated herein with special reference to the manufacture of shoes having skeleton insoles, i. e., insoles formed with open or skeletonized 5 foreparts.

In the manufacture of shoes having skeleton insoles it is usually found desirable to attach to the inner surface of the forepart of each insole a thin piece of relatively stiff material to serve 10 as a temporary reinforcement against the strains to which the insole is subjected during the lasting of the shoe and later as the result of the reaction of the lasted upper after the latter has been secured to the insole. Finally, after the 15 shoe has been removed from the last, the reinforcing piece is pulled out from the inside of the shoe. Moreover, it is also usually desirable to provide a filler of some sort for the space within the overlasted margins of the upper materials 20 in order to avoid the formation of a hollow in the outer surface of the forepart of the outsole.

The present invention provides various improvements in the manufacture of shoes having skeleton insoles including improvements relating 25 to the reinforcing of the skeleton insole, the trimming of the overlasted margins of the upper, and the filling of the space within the trimmed upper margins.

As illustrated, the forepart of the skeleton insole is reinforced by means of a piece of relatively stiff reinforcing material which overlies the opening in the insole and is temporarily secured by means of cement to the adjacent marginal portion at the outer side of the insole, the 30 reinforcing piece having an edge contour corresponding to that of the forepart of the insole but being substantially smaller than the insole so as to leave a substantial width of insole margin exposed to receive the lasting allowance of the 35 upper and the reinforcing piece being of substantial thickness so that its edge will constitute a perpendicular lasting shoulder for deflecting into upstanding position the inner edge portion of the lasting allowance in order to facilitate the trimming of the upper. As also illustrated herein, 40 after the upper has been worked over the last and the lasting allowance has been secured in overlasted position to the marginal portion of the insole with its edge portion upstanding around the reinforcing piece in the forepart of the shoe, the 45 reinforcing piece is removed by stripping it from the insole and the upstanding edge portion of the upper is trimmed so that its trimmed edge will be flush with the remaining overlasted portion thereof. The space within the trimmed

edges of the upper is then filled by means of a 5 filler piece having the same edge contour as that of the reinforcing piece so that it will accurately fit within and fill that space, the edge thickness of the filler piece preferably corresponding to that of the upper materials so as to insure against 10 the formation of any depression in the forepart of the outsole. Preferably, the filler piece is composed of soft yielding material, such as felt, in order to provide a cushioning effect in the 15 forepart of the shoe bottom and as shown the filler piece may be made thicker in its central portion than at its edge so as to insure the desired transverse convexity in the outsole. A regular outsole may be attached to the shoe bottom 20 by means of cement or otherwise or an outsole may be employed which has in its forepart an integral projection which is complementary to the opening in the insole in which case the filler piece will be only of such thickness as to compensate 25 for the thickness of the overlasted upper materials.

The invention will now be explained with reference to the accompanying drawing, in which

Fig. 1 is a perspective view of a reinforced 25 skeleton insole constructed in accordance with the present invention, the insole being applied to the bottom of a last;

Fig. 2 is a cross-sectional view of the forepart 30 of a shoe in the course of construction in accordance with my improved method, the shoe being shown as it appears after the upper has been secured in overlasted relation to the insole;

Fig. 3 is a perspective view of the shoe as it appears after the insole reinforcing piece has been 35 removed and before the upper has been trimmed;

Fig. 4 is a cross-sectional view of a portion of the forepart of the shoe illustrating the operation 40 of trimming the upper;

Fig. 5 is a cross-sectional view of a completed 45 shoe embodying a regular outsole; and

Fig. 6 is a view similar to Fig. 5 but showing an outsole having its forepart formed with an integral projection complementary to the opening 45 in the insole.

In the drawing 10 designates a skeleton insole having a central forepart opening 12, and 14 designates a temporary reinforcing piece which overlies the opening 12 and the adjacent portions of the forepart of the insole and is secured to the latter by cement, as indicated at 16 in Fig. 1, the cement being preferably rubber cement such as latex or other cement which will remain more or less viscous in use so that the reinforcing piece may be easily removed by stripping it from the 55

insole at a later stage in the manufacture of the shoe, as will hereinafter be explained. The reinforcing piece 14 corresponds in edge contour with that of the forepart of the insole but it is smaller 5 in size than the insole forepart so as to leave exposed between its edge and the edge of the insole a sufficient width of insole margin to enable the lasting allowance of a shoe upper to be secured in overlasted position to the insole. The reinforcing piece 14 is made of relatively stiff material such, for example, as fiberboard, so that it will reinforce the skeletonized forepart of the insole against the stresses to which it is to be subjected in the lasting of the shoe and it is of substantial 10 thickness and is died out or otherwise formed with its edge perpendicular to its faces so that the edge will be adapted to function as a perpendicular lasting shoulder for deflecting upwardly the inner portion of the lasting allowance 15 in the forepart of the shoe in a manner to facilitate the subsequent trimming of the upper. Preferably, the reinforcing piece 14 will be cemented to the insole before the insole has been applied to the last and while the insole is in a flat condition. 20

It may be here noted that the attachment of the reinforcing piece 14 to the insole enables the latter to be conveniently secured in place upon the bottom of a last by means of tacks driven through that portion of the reinforcing piece which overlies the opening in the forepart of the insole, thus rendering it practicable to employ metal-shod lasts of the type ordinarily used in the making of McKay-sewed shoes. Such a last is shown in the drawing at 18, the last having a metallic bottom plate 20 provided with the usual tack holes 22. As shown, the insole 10 is secured by three tacks 24, two of which extend through the reinforcing piece 14, through the two holes 22 in the forepart 40 of the last plate 20 and into the wood of the last, while the third tack 24 extends through the rear portion of the insole, through the rearmost hole 22 in the last plate 20 and into the last. It will be noted that the foremost tack holes 22, which 45 occupy their customary locations in the last plate, are so located as to be within the opening 12 in the insole and thus it will be apparent that if no reinforcing piece were employed to bridge the opening in the insole it would not be possible to 50 secure the forepart of the insole to the last by means of tacks. Inasmuch as many shoe manufacturers have large stocks of metal bottom lasts on hand and might not be disposed to purchase new lasts without metal bottoms for use in making shoes having skeleton insoles, it will be recognized that a substantial advantage results from the use of the temporary reinforcing piece 14 as a means for receiving tacks for temporarily securing the insole to the last. 55

In continuing with the practice of my improved method of making shoes the upper materials 30 of a shoe (herein shown as comprising a lining 32 and an upper 34) after having been assembled with the insole 10 on the last 18 and pulled over in the usual way, are lasted and the marginal portions thereof are secured in overlasted position to the insole. Various methods of lasting the upper materials may be practiced. The upper materials are herein illustrated as having been secured in overlasted position to the insole by means of cement except at the heel where tacks 36 are employed. In preparing for the attachment of the upper materials to the insole by means of cement a stripe of cement, for example rubber cement or latex, is applied to the margin of the insole either

before or after the insoles are applied to the last and cement is applied to the marginal portions of the upper materials, that is, to the side of the lining which is to face the insole and also between the lining and the upper. The upper materials are then worked over the last and over the marginal portion of the insole by means of suitable lasting operations. The lasting of the upper materials over the insole at the opposite sides of the forepart and shank portions of the shoe may be accomplished by means of a side lasting machine in the use of which one or more overlaying members operate progressively along the shoe bottom to wipe the upper materials inwardly over the marginal portions of the insole. As herein shown, staples 38 are employed, in addition to the cement, for securing the upper materials in overlasted position in the shank portion of the shoe. The operation of lasting the toe and heel portions of the shoe may advantageously be performed by means of a bed lasting machine of a well-known type such, for example, as the machine disclosed in United States Letters Patent No. 1,018,477, granted February 27, 1912, upon application of Matthias Brock. 15

The overlaying members of the side lasting machine and the toe plates of the bed lasting machine will wipe the margins of the upper materials inwardly over the insole and work them into the right angle between the surface of the insole and the perpendicular edge of the reinforcing piece 14, leaving them upstanding around the forepart of the shoe, as indicated at 40 in Figs. 2 and 3. As shown in Fig. 3, staples 38 may be employed in addition to the cement in the shank portion of the shoe for retaining the margins of the upper materials in overlasted position. As illustrated, cement alone is relied upon to maintain the upper materials in overlasted relation to the insole at the forepart and in the toe portion of the shoe, although if desired staples could be used either as temporary or permanent lasting fastenings in addition to the cement. 30

After the lasting operations have been completed the reinforcing piece 14 is removed by stripping it from the insole and the upper margins are trimmed. The trimming operation is facilitated by the fact that the inner edge portions of the upper margins have been deflected upwardly by engagement with the edge of the reinforcing piece so that they are disposed in substantially perpendicular relation to the insole. This arrangement of the edge portions of the upper materials in the forepart of the shoe makes it feasible to trim the upper by the use of a so-called turn shoe trimming machine of the general type of that disclosed in United States Letters Patent No. 429,065, granted May 27, 1890, upon application of H. S. Shaadt and F. L. Clark. As shown in Fig. 4, such a machine is provided with cooperating shear blades comprising an inner or stationary shear blade 42 and an outer or reciprocating shear blade 44. As also illustrated in Fig. 4, in order that the machine shall operate to trim the edge of the upper flush with the exposed surface of that portion of the upper which overlies the margin of the insole, the usual relation of the trimming blades has been reversed so that the inner or stationary blade 42 is lowermost and the outer or reciprocating blade 44 is uppermost. It will be seen that the outer end of the inner and lower blade 42, by engagement with the inner side of the upstanding margin of the upper, serves as a gage for properly locating the work relatively to the trimming blades. It will also be observed 40

that not only is the upstanding portion of the upper trimmed flush with the overlasted portion thereof, but the trimmed edge will be located in a position determined by the edge contour of the 5 reinforcing piece 14. Thus, by cutting out a filler piece so as to correspond in edge contour with that of the reinforcing piece 14, a filler piece may be obtained which is shaped so as accurately to fit within the space which is to be filled. A filler 10 piece thus cut to size is indicated at 48 in Fig. 5, the filler piece being of an edge thickness corresponding to the combined thickness of the upper materials so as to compensate for the thickness of the latter and thus to prevent the formation of a 15 hollow or sunken area in the outer or tread surface of the outsole which is subsequently to be attached to the shoe. Advantageously, the filler piece 48 may be composed of suitable soft or yielding material such as felt so as to provide a cushioning effect in the shoe. The marginal portions 20 of the filler piece may be beveled to correspond with the bevel around the edge of the opening 12 in the insole.

After filling the space within the overlasted 25 margins of the upper the shoe is ready to receive an outsole which may be laid and attached in any suitable manner. As shown in Fig. 5 the outsole 50 has been attached by means of cement, the margins of the outsole and the surfaces of the 30 overlasted upper materials having been previously roughened and coated with cement in a well-known manner.

It will be noted that in accordance with the 35 herein described method it is not necessary that the skeleton insole be split from an outsole so as to leave on the outsole a central projection complementary to the opening in the insole or that the marginal portion of the outsole be reduced to any substantial extent. However, if desired, a so-called complementary insole-outsole combination 40 may be employed, as illustrated in Fig. 6, wherein the outsole 52 has a central forepart projection 54 which is complementary to the opening in the insole and which would be adapted completely to 45 fill the opening in the insole if the overlasted margins of the upper were not interposed between the soles. In order to compensate for the thickness of the overlasted upper margins between the inner and outer soles in such cases, a filler piece 50 may be employed which, as shown, is advantageously of an edge thickness corresponding to that of the upper materials.

Having described my invention, what I claim as 55 new and desire to secure by Letters Patent of the United States is:

1. That improvement in methods of making shoes which consists in reinforcing a skeleton insole having a central forepart opening by temporarily securing to the forepart of the insole prior 60 to the application of the insole to a last a reinforcing piece of a size to cover said opening while leaving exposed at the forepart of the insole a sufficient width of margin to receive the lasting allowance of an upper, securing said insole to a last with said reinforcing piece at the outer side of the insole, working an upper over the last and securing its lasting allowance to the insole, removing said reinforcing piece from the insole, filling the opening within the insole, and 65 attaching an outsole.

2. That improvement in methods of making shoes which consists in reinforcing a skeleton insole having a central forepart opening by temporarily securing to the forepart of the insole prior 70 to the application of the insole to a last a rela-

tively stiff reinforcing piece of a size to cover said opening while leaving exposed at the forepart of the insole a sufficient width of margin to receive the lasting allowance of an upper, temporarily securing said insole to a last with said reinforcing piece at the outer side of the insole, working an upper over the last and securing its lasting allowance to the insole, removing said reinforcing piece from the insole, trimming the upper, inserting in the space within the trimmed edges of 10 the upper a relatively soft and flexible filler piece, and attaching an outsole.

3. That improvement in methods of making shoes which consists in reinforcing an insole having a central opening in its forepart by laying 15 over said opening and temporarily securing to the adjacent portion of the outer side of the insole a reinforcing piece of substantial thickness and of a contour corresponding to that of the forepart of the insole but of a size substantially 20 smaller than said forepart, thereby leaving exposed a substantial width of insole margin for receiving the lasting allowance of an upper and adapting the edge of said reinforcing piece to serve as a lasting shoulder, assembling said reinforced insole with an upper on a last, working the upper over the last and over the marginal portion of the insole and against said lasting shoulder and securing it in overlasted position to the insole thereby leaving a portion of the 30 upper upstanding beside said shoulder, removing said reinforcing piece, trimming the upper thereby removing the upstanding portion thereof, and attaching an outsole.

4. That improvement in methods of making 35 shoes which consists in reinforcing the forepart of a skeleton insole by adhesively securing thereto a reinforcing piece of substantial thickness and of a contour corresponding to but smaller than that of the insole, assembling the insole 40 with an upper on a last, lasting the upper and securing it in overlasted position upon the insole with the marginal portion of the upper upstanding along the edge of said reinforcing piece, stripping the reinforcing piece from the insole and 45 cutting away the upstanding edge of the upper thereby providing a space within the trimmed edges of the upper corresponding in shape to that of said reinforcing piece, filling said space with a piece of flexible material cut to the same 50 shape as said reinforcing piece and of a thickness to compensate for the thickness of the upper, and attaching an outsole.

5. That improvement in methods of making 55 shoes which consists in cementing to one side of the forepart of a skeletonized insole a reinforcing piece of substantial thickness and of a contour corresponding to but smaller than that of the insole, assembling the insole with an upper on a last, working the upper over the last and over 60 the marginal portion of the insole and into the angle formed between the edge of said reinforcing piece and the adjacent surface of the insole, thereby causing the edge portion of the upper to assume an upstanding position along the edge 65 of said reinforcing piece and securing the upper in overlasted relation to the insole, stripping said reinforcing piece from the insole, trimming the upstanding edge portion of the upper flush with the outer surface of that portion which 70 overlies the insole, inserting a filler piece in the location formerly occupied by said reinforcing piece, and attaching an outsole.

6. That improvement in methods of making 75 shoes which consists in cementing to one side of

- the forepart of a skeletonized insole a reinforcing piece of substantial thickness and of a contour corresponding to but smaller than that of the insole, assembling the insole with an upper on a last, working the upper over the last and over the marginal portion of the insole and into the angle formed between the edge of said reinforcing piece and the adjacent surface of the insole, thereby causing the edge portion of the upper 10 to assume an upstanding position along the edge of said reinforcing piece and securing the upper in overlasted relation to the insole, stripping said reinforcing piece from the insole, trimming the upstanding edge portion of the upper flush 15 with the outer surface of that portion which overlies the insole, applying to the space within the trimmed margin of the upper a filler piece of an edge thickness equal to that of the upper materials and of a contour corresponding to 20 that of said reinforcing piece, and attaching an outsole having a central forepart projection complementary to the opening in the insole.

7. That improvement in methods of making

shoes which consists in reinforcing an insole having a central opening in its forepart by laying over said opening and temporarily securing to the adjacent portion of the insole a reinforcing piece of substantial thickness and of a contour 5 corresponding to that of the forepart of the insole but of a size substantially smaller than said forepart so that the edge of said reinforcing piece is adapted to serve as a lasting shoulder, placing said insole upon a last of the type used 10 in making McKay-sewed shoes, said last having a metallic bottom plate provided with the usual tack holes, securing the insole to the last by means of tacks driven through said reinforcing piece and through said tack holes and into the 15 last, assembling an upper with the insole on the last, working the upper over the last and securing its margin in overlasted position upon the insole, withdrawing said lasting tacks and removing said reinforcing piece from the insole, 20 trimming the upper, and attaching an outsole.

CHESTER D. TURNER.
